DESIGN FOR A PRESSING IRON

Fred A. Miller, St. Johns, Mo., assignor of one-half to Roland M. Klemme, St. Louis, Mo.

Application November 16, 1944, Serial No. 116,360

Term of patent 14 years

(Cl. D49—6)

To all whom it may concern:

Be it known that I, Fred A. Miller, a citizen of the United States of America, residing at St. Johns, in the county of St. Louis, State of Missouri, have invented a new, original, and ornamental Design for a Pressing Iron, of which the following is a specification, reference being had to the accompanying drawing, forming a part thereof.

Fig. 1 is a perspective view of a pressing iron embodying my new design.

Fig. 2 is a top plan view of the pressing iron illustrated in Fig. 1.

Fig. 3 is a side elevational view of the pressing iron illustrated in Figs. 1 and 2.

I claim:

The ornamental design for a pressing iron, as shown.

FRED A. MILLER.
